UNITED STATES PATENT OFFICE.

FRANK S. RECE, OF DALLAS, TEXAS, ASSIGNOR OF ONE-HALF TO EDWARD H. EPPERSON, OF DALLAS, TEXAS.

POULTRY-DECAPITATOR.

1,310,294.

Specification of Letters Patent. Patented July 15, 1919.

Application filed September 25, 1918. Serial No. 255,646.

To all whom it may concern:

Be it known that I, FRANK S. RECE, a citizen of the United States, residing at Dallas, in the county of Dallas and State of Texas, have invented certain new and useful Improvements in Poultry-Decapitators, of which the following is a specification.

This invention relates to poultry decapitators and has as one of its objects to provide a device for this purpose by the use of which fowls may be readily and quickly beheaded in a humane manner.

Another object of the invention is to so construct the stock of the decapitator that, without causing the fowl any pain, its neck, when placed in position for the operation of the blade member of the device, will be held against displacement. Incidentally the invention contemplates so constructing the stock of the device that the neck of the fowl may be so positioned that when the blade member of the device is actuated to behead the fowl, the neck will be severed close to the head so that where a number of the fowls are to be decapitated for the market, their necks will appear of even length and will be evenly cut and there will be a minimum waste of the fowl as a result of its decapitation.

30 A further object of the invention is to provide a device of the class described so constructed that it will be inexpensive to manufacture and may in fact be produced almost wholly of stamped sheet metal.

35 A further object of the invention is to so construct and mount the blade member of the device that the same may be readily disconnected from the stock of the device for the purpose of sharpening the cutting edge.

40 Still another object of the invention is to provide a poultry decapitator of such construction that it may be readily secured to any suitable block or post or even to the side of a house, the device being adapted for 45 use in either a vertical or horizontal position.

In the accompanying drawings:

Figure 1 is a perspective view of the decapitator embodying the present invention;

50 Fig. 2 is a vertical front to rear sectional view therethrough;

Fig. 3 is a horizontal sectional view on the line 3—3 of Fig. 1;

Fig. 4 is a front elevation of the device, 55 the blade member being shown in full lines

in retracted position and in dotted lines in advanced position;

Fig. 5 is a group perspective view illustrating the several parts comprising the decapitator disassembled;

60 Fig. 6 is a plan view of the blank from which the stock of the decapitator is formed.

Generally speaking the decapitator embodies a stock and a blade member, the stock being adapted to be attached to any 65 suitable support and being provided with a neck receiving opening, and the blade member being mounted within the stock for sliding movement in a direction to cause its cutting edge to pass the said opening.

70 The stock, as also the blade member, is preferably formed from a sheet metal blank and said stock is indicated in general in the drawings by the numeral 1 and comprises flat side members 2 which occupy parallel 75 planes and are slightly spaced apart so as to movably receive between them the blade member of the device as will be presently fully explained. The lower end portion of each of the side members 2 of the stock is 80 bent laterally outwardly to provide an attaching base member 3 and these members are formed with openings 4 for the passage of screws or other securing elements 5 whereby the base of the stock may be se- 85

90 cured to a wooden or other suitable block 6 or to a post or even to the side of a house, the device, as before stated, being adapted for use either in a vertical position or in a horizontal position. The rear edge portion 90 of each of the spaced members 2 of the stock is bent laterally outwardly at right angles to the plane of the said member to provide a reinforcing wing or flange 7 and the lower end portions of these flanges or wings are 95

100 bent rearwardly at right angles as indicated by the numeral 8 so as to supplement the base portions 3 in firmly bracing the stock upon its supporting block 6. The entire stock is formed from a single integral sheet metal blank and this blank is folded midway between its ends in forming the side members 2 of the stock so that as a result the said side members are united at their upper ends by a connecting portion or loop 105

9, which for a purpose to be presently explained is formed with a slot 10 located immediately above the space between the said spaced members 2. Near their upper ends, the side members 2 are bent outwardly 110

as indicated by the numeral 11, substantially at right angles to their planes and thence upwardly preferably in substantially converging planes to form the sides 12 of an 5 open or looped head 13 which is designed to house the spring provided for retracting the blade member as will be presently explained. In providing the portions 11, shoulders 14 are formed located at opposite 10 sides of the space between the members 2, as clearly shown in Fig. 4 of the drawings.

The side members 2 of the stock 1 are formed with oppositely located neck receiving openings indicated in general by the 15 numeral 15 and each of these openings is of L shape as shown, being formed with a mouth or branch 16 which opens through the forward edge of the respective side member 2 and a second branch or body 17 20 which extends downwardly at right angles from the inner end of the branch 16, the bottom walls of the branches 17 being preferably concave as indicated by the numeral 18 so as to more or less snugly engage the 25 neck of the fowl to be decapitated. The body of the opening in each side member 2 extends parallel to the forward edge of the said side member and the material of the side member between its said forward edge 30 and the opening is preferably slightly bent outwardly into lips 19 so as to provide between the side members a guide for the cutting blade member of the device, as clearly shown in Figs. 1, 3, 4 and 5 of the drawings. 35 The branches 16 and 17 of the opening 15 are preferably of a width just sufficient to more or less snugly accommodate the neck of a fowl of ordinary size and are consequently of a width less than sufficient to permit the 40 passage or withdrawal through the opening of the head of the fowl. Thus when the neck of a fowl is introduced into the opening through its mouth 16 and is then moved downwardly into the body 17 until it rests 45 in the concavity of the wall 18, the fowl may be drawn to one side until its head engages against one or the other of the side members of the stock and then when the blade member is actuated it will sever the 50 neck close to the head. Of course, due to the angular disposition of the branches 16 and 17 of the neck receiving opening, there is little likelihood of the movements of a fowl causing disengagement of its neck from the 55 body 17 after the neck has once been disposed within the branch and there is consequently little likelihood of mutilation being caused at the time of operation of the blade member.

60 The blade member is, as before stated, preferably formed of sheet metal and the same, indicated in general by the numeral 20, includes a shank 21 which has its upper portion slidably fitted through the slot 10 65 and which is broadened at its lower end to

provide the blade proper, indicated by the numeral 22. The cutting edge of the blade is indicated by the numeral 23 and the same extends diagonally of the longitudinal medial line of the shank 21. The shank and 70 blade proper occupy a common plane and the lower portion of the shank and the said blade proper fit slidably between the opposing faces of the side members 2 of the stock, the blade being so positioned that its cutting edge 23 will be inclined upwardly and in the direction of the rear side of the stock so that its forward end will constitute its advancing end and will first pass across the 75 neck receiving opening. Thus when the 80 blade member is moved downwardly, it will first move across the branch 16 and effectually close this branch to prevent any disengagement of the neck of the fowl from the neck receiving opening, and toward the 85 latter part of the movement of the blade member the cutting edge of the blade will pass downwardly beside the branch 17 and sever the neck of the fowl with a shearing cut. In order to further guide the shank 90 of the blade member and in order to prevent spreading of the side members 2 of the stock 1, a guide member such as clearly shown in 95 Figs. 2 and 5 of the drawings and indicated in general by the numeral 24, is preferably 100 provided. This member comprises a connecting portion 25 and side portions 26 which latter are fitted through slots 27 formed in the sides 2 of the stock of the device, the said sides 26 being formed with 105 openings 28 through which is passed a pin 29 which rests against the outer face of one side member 2 while the connecting portion 25 of the member 24 rests against the outer face of the other member 2. Thus, as stated, 110 105 the members 2 are held against separation or spreading and at the same time, inasmuch as the shank of the blade member works between the sides 26 of the said member 24 as shown in Fig. 2 of the drawings, 110 the said shank is effectually guided in its sliding movement. It is preferable that the shank 21 be reduced in width from its junction with the blade proper 22 to a point normally located within the head 13 of the stock 115 and in thus reducing the shank, a shoulder 30 is formed at the upper end of its reduced portion against which bears the upper end of a coiled compression spring 31 which is fitted upon the reduced portion of the shank 120 and which at its lower end bears upon the shoulders 14 at the bottom of the head 13. This spring serves to normally hold the blade member retracted and to automatically retract the same after it has been actuated and released, and the upward movement of the blade member is limited by the engagement of the upper edge of the blade 22 with the side portions 26 of the member 24 as clearly shown in Figs. 2 and 4 of the 130

drawings. The shank of the blade member may be provided with any desired form of handle against which pressure may be exerted and which handle, however, is to be 5 detachably connected with the shank so that the blade member may be bodily removed or disconnected from the stock of the device whenever it is desired to sharpen the cutting edge 23. While various types of handles 10 may be provided for the purpose stated, one well suited for the purpose is illustrated in the drawings and is formed from a strip of sheet metal bent to provide a shank 32 and a head 33 extending at right angles to the 15 plane of the shank and against which head pressure may be exerted for the purpose of actuating the blade member. At its lower end, the shank is reduced to provide a tongue 34 which is bent at right angles to the shank and which is fitted through a slot 35 formed in the upper end portion of the shank 21 of the blade member, a collar or sleeve 36 being slidably fitted on the shanks 21 and 32 and movable to position to embrace both shanks as shown in Figs. 1, 2 and 20 4 of the drawings, whereby to prevent disengagement of the tongue 34 from the slot 35. Of course, this collar or sleeve may be slid upwardly upon the shank until it clears 25 the upper end of the shank 21 whereupon the handle may be readily disconnected from the shank of the blade member.

As stated, various types of handles may be provided and also, in lieu of the member 30 24, bolts or the like may be detachably fitted through the spaced side members 2 of the stock.

In the use of the device, the neck of the fowl to be decapitated is introduced into 40 the lower or inner end of the branch 17 of the opening 15 and when properly positioned, downward pressure is exerted against the head 33 of the handle member thus forcing the blade 22 toward the block 45 6 and severing the neck of the fowl. The outwardly bent portions 19 of the side members of the stock serve to effectually guide the blade in such movement inasmuch as the advancing or forward end of the blade 50 enters between these portions immediately after passing across the branch 16 of the opening 15. When it is desired to sharpen the cutting edge of the blade, the blade member may be bodily removed from the stock by removing the pin 29 and the member 24, disconnecting the handle for the 55 blade member, and then sliding the blade member downwardly and at the same time swinging the lower end thereof forwardly 60 until the upper end of the shank of the blade member passes through the slot 10.

The strength of the spring is in practice to be no greater than is actually required to fully retract the cutting member after the 65 latter has been actuated and released, there-

by avoiding unnecessary expenditure of force in the actuation of the said cutting member.

It will be evident from the foregoing description of the invention that the same will 70 prove highly desirable for domestic use as it can be successfully employed by women and others who are not skilful enough to perform the operation with an ax or a hatchet, or who are averse thereto, and affords to all a more acceptable method than the wringing of the fowl's neck.

Having thus described the invention, what is claimed as new is:

1. In a device of the class described, a 80 stock formed of a single blank of sheet metal bent at its midlength into a looped head and below the same into spaced, flat side members provided along their rear edges with rightangular wings, the lower ends of said 85 members and wings being bent outward in a single horizontal plane to produce a supporting base, said side stock having a transverse opening; combined with an element slidably vertically within said stock and having a member at its lower end movable across said opening.

2. In a device of the class described, a 90 stock formed of a single blank of sheet metal bent at its midlength into a looped head and below the same into spaced, flat side members provided along their lower ends with outturned portions forming a supporting base, said side members having registering 95 openings; combined with an element including a member which in its movement coats with said openings, a shank rising from the member within the stock and through and above its head, and a handle at the upper end of said shank, and means located within 100 105 said head for normally raising said element.

3. In a decapitator, a stock provided with a neck receiving opening of L shape having its mouth extending inwardly from one edge thereof and its body extending downward 110 from the inner end of the mouth and longitudinally of the stock, and a blade member guided longitudinally of the stock and having a cutting edge disposed to cross the body of the opening, the said cutting edge being 115 inclined in the direction of that edge of the stock opposite the edge through which said mouth opens.

4. In a decapitator, a stock including flat, spaced side portions provided with aligned 120 L-shaped openings whose bodies are upright and whose mouths open through one edge of said side portions, the lips of the latter beneath the mouths of the openings being spread apart slightly, and a blade guided 125 for vertical movement between said side portions and of a length to extend across the bodies of said openings, one end of the blade adapted to move between said lips.

5. In a decapitator, a stock having spaced 130

side members and an open head, the side members having a neck receiving opening, a blade member slidably mounted between the side members and having a shank extending slidably through the head, a spring within the head normally holding the blade member elevated, the juncture of the shank with the blade proper providing a shoulder, and means for guiding the shank including spaced elements connecting said side members of the stock and engageable by the shoulder to limit the rise of the blade member under the influence of the spring.

6. In a decapitator, a stock having spaced side members provided with oppositely located neck receiving openings extending inwardly from one edge thereof, and a blade slideable vertically between the said members and across the body of said opening, the 20 blade having its cutting edge inclined and therefore having one end located in advance of the other, and said members below the mouth of the opening being relatively spread out of the path of the advanced end of the 25 cutting edge.

7. In a decapitator, a stock provided at its upper end with an open head and comprising in its lower portion spaced side members, the bottom of the interior of the head 30 providing a shoulder at the upper ends of the said side members, the said side members having a neck receiving opening, a blade member slidably movable between the side members and through the head, and a spring 35 upon the shank of the blade member resting at its lower end upon the shoulder and at its upper end engaging an abutment portion of the shank.

8. In a decapitator, a stock comprising spaced side members, a guide means including spaced elements extending through the side members, and a blade having a shank slidably fitted between the side members of the stock and guided by the said elements 45 of the guiding means, the spaced side members of the stock having a neck receiving opening across which the cutting edge of the blade is to move.

9. In a decapitator, a stock having spaced side members and an open head providing a connection between the upper ends of the side members, the side members having a neck receiving opening, the juncture of the side members with the head providing a 50

shoulder within the head, a blade member 55 slidably mounted between the side members and having a shank extending slidably through the head, the shank of the blade member being provided with a shoulder lying within the head, and a spring upon the shank bearing at one end against the shoulder upon the shank and at its other end against the shoulder within the head and normally holding the blade member retracted.

10. In a decapitator, a stock having spaced side members and an open head providing a connection between the upper ends of the side members, the side members having a neck receiving opening, the juncture of the 70 side members with the head providing a shoulder within the head, a blade member slidably mounted between the side members and having a shank extending slidably through the head, the shank of the blade 75 member being provided with a shoulder lying within the head, a spring upon the shank bearing at one end against the shoulder upon the shank and at its other end against the shoulder within the head and normally holding the blade member retracted.

11. In a decapitator, a stock having spaced 80 side members and an open head providing a connection between the upper ends of the side members, the side members having a neck receiving opening, the juncture of the side members with the head providing a shoulder within the head, a blade member slidably mounted between the side members and having a shank extending slidably through the head, the shank of the blade 85 member being provided with a shoulder lying within the head, a spring coiled upon the shank within the head and expanding between said shoulders to normally hold the blade member elevated, means for limiting the rise of said member, and a detachable 90 handle at its upper end.

In testimony whereof I affix my signature.
FRANK S. RECE.
